PINCUSHION

Filed May 24, 1926

FIG. 1.

FIG. 2.

FIG. 3.

Edmund Ryder
INVENTOR.

BY

Harold C. Ryden
ATTORNEY.

UNITED STATES PATENT OFFICE.

EDMUND RYDER, OF OTTAWA, ONTARIO, CANADA.

PIN CUSHION.

Application filed May 24, 1926. Serial No. 111,356.

My present invention relates to improvements in pincushions, more particularly characterized as a holder for the conventional straight shank pin extensively used 5 in offices and other places of business, the principal object of the invention being to provide an article of this nature which is simple to manufacture and keep in order and which will be symmetrical and attractive in appearance.

Other objects and advantages of my invention will become apparent ensuing a perusal of the following specification read in conjunction with the annexed drawings, 15 in which:

Fig. 1 is a longitudinal medial vertical section of my invention, and,

Fig. 2 is a transverse medial vertical section thereof.

20 Fig. 3 is an enlarged detail view of a modified form of the base and weight portions of my invention.

In the two views, like characters of reference designate corresponding parts.

25 Referring in detail to the drawings, the numeral 3 designates the base section, which includes an upstanding marginal wall 4, providing a receptacle for the cushioning material 5, the latter being retained in place by the flexible covering 6 of any suitable fabric or the like. This covering is secured as shown by the cushioning material retaining member 7, which fits over the edges of the covering material overlying the upper edge of the 30 marginal wall 4, the member 7 being provided with an inwardly extending flange 8 for this purpose. The ends of the member 7 may be relatively thicker than the sides thereof to receive the screws 9 extending through the base 3.

40 When it is desired to use the device as a paper weight and when the same is constructed of relatively light metal or such other material as may be employed, I may 45 insert a weight 10 of lead or equivalent ma-

terial in the base 3, which may be retained in position by screws 11.

To replace the covering material 6 when the same has been used to such an extent that the appearance of the same is impaired or 50 when such covering material is worn out and will no longer fulfill its purpose, the screws 9 extending through the covering material retaining member 7 are removed and the latter is lifted from off the base 3 so that 55 the covering material 6 may be removed and replaced.

Referring more particularly to Fig. 3, it will be noted that the base section 3 is provided with angularly directed openings 60 therethrough and instead of the weight 10 being inserted into the base 3, the molten material which is to form the weight 10 is poured so that portions thereof will fill the angularly directed openings formed through 65 the base. When the material, forming the weight 10, hardens, the portions which have filled the angularly directed openings in the base, will be locked so as to permanently retain the weight secure to the upper face of 70 the base 3.

The device provides a very unique pin holder in that it will readily accommodate a considerable number of pins when made in a convenient size and it is very symmetrical 75 in appearance and may also be utilized as a paper weight as previously suggested.

What I claim as new is:

A device of the character described, comprising a base, having an upstanding marginal wall; said base having angularly directed openings formed therethrough; an auxiliary weight, formed from material poured over said base; said weight having integral retainer portions locked in said 85 openings when said material becomes hardened; a cushioning member and a means for retaining said member on said base.

In testimony whereof I affix my signature.

EDMUND RYDER.
